DUCTOR ROLL CONTROLLING MECHANISM

Harry W. Faeber, Larchmont, N. Y., assignor to
Time, Incorporated, New York, N. Y., a corpora-
tion of New York

Application January 14, 1950, Serial No. 138,617

6 Claims. (Cl. 101—351)

1

The present invention relates to a mechanism for controlling the lateral movement of a ductor roll for a printing press or paper coating machine.

It has become conventional practice to mount ductor rolls on oscillating arms. In modern high speed printing presses, ductor rolls so mounted must necessarily oscillate at high frequencies. In practice it has been found that ductor rolls mounted on arms oscillating at high frequencies have a tendency to bounce from the adjacent distributor or fountain roll instead of making firm contact with them.

In accordance with the present invention, a ductor roll is mounted for rotation and for lateral movement back and forth between a first terminal position, in which the ductor roll makes contact with a fountain roll, and a second terminal position, in which the ductor roll makes contact with a distributor roll. In addition, means are provided for releasably locking the ductor roll against lateral movement and thereby interrupting the transfer of ink or the like from a fountain roll to a distributor roll.

In a preferred embodiment of the invention, each end of the ductor roll shaft is mounted for rotation in a bearing which in turn is eccentrically mounted in a housing that is adjustably secured to a stationary frame member of the machine, i. e., the ductor roll bearing is movable about an axis in the housing that is parallel to but laterally displaced from the axis of rotation of the ductor roll. The ductor roll bearing is mounted on an eccentric shaft member in the housing and, during the operation of the machine, the shaft member is rocked back and forth through an angle of substantially 180° by the operation of a rack and pinion arrangement actuated by a cam so that as the shaft member turns upon its axis of rotation, the axis of rotation of the ductor roll will be displaced between two terminal positions to the end that the ductor roll will make alternate contact with a fountain roll and a distributor roll.

By positioning the axis of the eccentric shaft in such a manner that it lies in a plane of reference intersecting both terminal positions of the ductor roll bearing and the axes of the adjacent fountain and distributor rolls, the ductor roll is momentarily locked against bouncing when it makes contact with either of the two adjacent rolls.

A locking device is provided to selectively lock the eccentric shaft member against rotation on its own axis of rotation when the axis of rotation

2

of the ductor roll is near the terminal position adjacent the distributor roll. While the eccentric shaft member is so locked, the transfer of ink or the like will be interrupted. In the preferred embodiment of the invention, means are provided automatically to actuate the locking device when, e. g., the web to be printed or coated is broken or the impression system is thrown into the "off" position. Upon release of the locking device, the ductor roll will be free to oscillate laterally between the distributor roll and the ductor roll.

One advantage of the present invention is that it provides an oscillating ductor roll mechanism that effectively and momentarily locks the ductor roll against lateral movement in each of its terminal positions and therefore insures firm contact with adjacent rolls and prevents objectionable bouncing.

Another advantage is that it provides a mechanism for automatically or manually interrupting the lateral movement of an oscillating ductor roll and consequently, of interrupting the transfer of ink or other material from a fountain roll to a distributor roll.

A further advantage is that it provides a mechanism for moving a ductor roll back and forth for alternate contact with a fountain roll and a distributor roll wherein the speed of lateral movement of the ductor roll follows a harmonic curve and the ductor roll is thus eased into alternate contact with the adjacent rolls.

One embodiment of the mechanism of this invention is illustrated, by way of example only, in the accompanying drawing wherein:

Figure 1 is a plan view of the device as mounted on one side of the frame only;

Figure 2 is a part sectional view in elevation of the mechanism illustrated in Figure 1 taken along section line 2—2;

Figure 3 is a detailed end view in elevation of the bearing for a ductor roll;

Figure 4 is a part sectional end view in elevation taken along section line 4—4 of Figure 2;

Figure 5 is a sectional view in elevation taken on section line 5—5 of Figure 1; and

Figure 6 is a schematic illustration of an automatic control system for actuating the locking device.

While the following description of the invention with reference to the drawing describes a preferred embodiment of the mechanism as it is applied to one side of the machine, it is to be understood that a similar device will be utilized at the other side of the machine to support the

other end of the ductor roll. The description of the invention will be confined to one of these mechanisms only in order to avoid unnecessary duplication.

Referring now to the drawing, one end of a ductor roll 10 is shown supported in a split journal ductor roll bearing 11 having an eccentric shaft member 12 extending into a housing 14 secured adjustably to a frame member 16 by bolts 17 passing through slots 19 in the base 20 of the housing. One end of a lateral adjusting screw 21 is in threaded engagement with the housing 14 at 22 and the other end is provided with a flange member 23 and a hexagonal head member 24 rotatably secured against axial movement relative to the frame member 16 by means of a bracket 26.

The shaft member 12 of the ductor roll bearing 11 is mounted for rotation in the housing 14 and one end thereof is provided with a gear 27 that meshes with the spur gear 29 of an idler shaft 30. A pinion 31 keyed by key 32 to the auxiliary shaft 30 is in meshing engagement with a spring-biased rack 34 slideable vertically in the housing 14 and actuated by a rocker arm 36 attached to a rocker shaft 37.

The lower end of the rack 34 is provided with a recess 38 engageable, when the rack is just below its upper terminal position, by a locking finger 39 pivoted on a stud 40 and actuated by a spring-biased control rod 41 provided with spring 42, a washer 43, a stop 44, a pair of notches 46 and 47, and a knob 48. To allow the finger 39 to enter the recess 38, the relationship of the recess to the rack 34 is such that the top of the recess 38 is slightly above the engagement position with the locking finger when ductor roll 10 is in contact with the distributor roll. The clearance between the recess 38 and the finger 39, while in engagement, is sufficient to permit the rocker arm 36 to move to its uppermost position in a succeeding stroke without subjecting any of the working parts to excessive stress. The rod 41 is movable through a guard member 49 having a fixed plate 50 adapted to engage with the notches 46 and 47.

As shown in Figure 3, the ductor bearing 11 may be of the split journal type having a base section 51 and a cap 52 pivoted at 54 and locked into position by means of a wing nut 56. The center line 57 of the ductor roll bearing 11 is laterally displaced from the center line 59 of the eccentric shaft member 12 so that as the shaft member is rotated, the ductor roll 10 will move laterally between the distributor roll 60 and the fountain roll 61.

In operation, each end of the shaft 10a of the ductor roll 10 is rotatably secured in the split journal bearing 11 by tightening the wing nut 56 to close the cap 52. If it is desired to stop the oscillating motion of the ductor roll 10 for interrupting the ink feed, notch 47 is lifted out of engagement with plate 50 by means of knob 48. Then, when the rack 34 is just below its uppermost position, as shown in phantom in Figure 4, the control rod 41 is urged, by spring 42, to engage the finger 39 with the recess 38 so as to prevent further substantial eccentric movement of the ductor roll bearing 11 about the longitudinal axis of the shaft member 12, the clearance between the finger 39 and the top and bottom of the recess 38 being sufficient, however, to permit the rocker arm 36 to continue its motion without subjecting any of the parts to excessive stress or damage. The control rod 41 will then be locked in the position shown in phantom in Figures 1 and 2 by en-

gagement of the plate 50 with the recess 46. When the locking finger 39 is disengaged from the recess 38 by disengaging notch 46 and moving the control rod 41 to engage with the other notch 47, the rack 34 and the ductor roll 10 are free to resume their respective motions.

When the machine is set into operation, the rocker shaft 37 acting through rocker arm 36 in cooperation with the spring 62 acting on the rack 10 34 will cause the rack to reciprocate in a vertical direction. The gear teeth 35 on the rack 34 engage with the pinion 31 of the auxiliary shaft 30 to impart a rocking motion thereto and the gear 29 on said auxiliary shaft 30 engages with the gear 27 on the shaft member 12 so as to transmit the rocking motion to the ductor roll bearing 11. Due to the eccentricity of the ductor roll bearing relative to the shaft member 12, the center line of the ductor roll will be displaced laterally from one side of the center line of the shaft member to the other and so on so that the ductor roll will come into alternate contact with the fountain roll 61 and the distributor roll 60.

In the preferred embodiment, the eccentric shaft member 12 is rocked back and forth through an angle of substantially 180° so that the axis of the ductor roll will lie in a plane of reference intersecting the axes of the shaft member 12, the distributor roll and the fountain roll when the ductor roll reaches a terminal position adjacent either of the other rolls. The shaft member 12 is therefore directly in line with reaction force applied to the ductor roll when it makes contact with an adjacent roll and thereby momentarily locks the ductor roll against bouncing.

It is within the scope of this invention to actuate the locking mechanism automatically so that the transfer of ink or other liquid will be interrupted immediately upon interruption of the printing operation for any reason. One embodiment of an apparatus to accomplish this desirable result is illustrated in Figure 6. In this arrangement, wherein a plate cylinder, impression cylinder and web, are shown schematically and designated by reference numerals 62, 64 and 66, respectively, a web follower 67, mounted on a lever 69 of a web break detector switch pivoted at 70, is urged by a spring 71 to bear against the moving web 66. The control rod 41a, which is slideably mounted in a fixed guard member 49a or the like, is normally urged in an inwardly direction by a compression spring 42a bearing at one end against member 49a and at the other against a collar 44a secured to the rod. If the web 66 should break, the spring 71 will cause the lever arm 69 to rotate in a clockwise direction about the fulcrum 70 and open an electrical circuit to deenergize a solenoid 72 and thereby release the rod 41a for movement inwardly under the influence of the compression spring 42a and urge the finger 39 to engage the recess 38 and thereby lock the ductor roll against further substantial lateral motion. When the web 66 is replaced in operative position, the circuit is closed again by the web detector switch and the solenoid 72 is energized to withdraw the finger 39 from engagement with the recess 38. If, on the other hand, the printing operation is halted for any reason by withdrawing the plate cylinder 62 to the "off" impression position shown in phantom, the relay 74 becomes de-energized to open the circuit to the solenoid 72 and thereby lock the motion of the ductor roll.

It is to be understood that the details of the mechanism herein described may be altered or modified considerably without departing from the

scope of this invention. Thus, for example, the eccentric mechanism need not necessarily be rocked through an angle of substantially 180°, the rack and pinion arrangement may be replaced by a suitable crank and pin arrangement and the electrical system illustrated in Figure 6 may be replaced by any other suitable actuating system such as an air or hydraulically operated system. All such modifications and alterations are intended to be included within the scope of this invention as defined in the appended claims.

I claim:

1. Ductor roll controlling mechanism comprising a housing, a shaft rotatable in the housing, a ductor roll bearing member mounted eccentrically on the shaft for movement back and forth between two terminal positions, the axis of the shaft lying in a plane of reference intersecting both terminal positions of the bearing member, a rack reciprocable in the housing, gear means connecting the shaft and the rack for rocking the shaft to move the bearing member from one terminal position to the other, a movable finger adjacent the rack, and a recess in the rack engageable by the movable finger for releasably locking the bearing member adjacent one of its terminal positions.

2. Ductor roll controlling mechanism comprising a housing, a shaft rotatable in the housing, a bearing member for supporting a ductor roll for rotation on an axis parallel to the axis of the shaft, said bearing member being mounted eccentrically on the shaft, means for rocking the shaft to move the bearing member back and forth between two terminal positions and in a direction perpendicular to the axis of the shaft, and means for releasably locking the shaft against rocking when the bearing member is adjacent one of its terminal positions, said releasable locking means comprising a member spring-biased for engaging with the rocking means releasably to lock the shaft against rocking in the housing, said member normally being maintained out of engagement with the rocking means by an energized electromagnetic means, and a web follower spring biased to ride on a web under tension, said web follower being adapted, upon a release in tension of the web, to open the circuit energizing the electromagnetic means and thereby actuate the spring-biased member to engage the rocking means and lock the shaft against rocking.

3. Control mechanism for a ductor roll movable laterally between a first contact position with a fountain roll and a second contact position with a distributor roll, which comprises a housing; a shaft rotatable in the housing; a bearing member for supporting the ductor roll for rotation on an axis parallel to the axis of the shaft, said bearing member being mounted eccentrically on the shaft for movement about the shaft; means for rocking the shaft to move the bearing member back and forth between the first and second contact positions of the ductor roll, the axes of the shaft, the ductor roll and one of the fountain and distributor rolls lying in a plane of reference when the ductor roll is in contact position with said one of the fountain and distributor rolls; and means for releasably locking the shaft against rocking when the ductor roll is in one of its first and second contact positions.

4. Control mechanism for a ductor roll movable laterally between a first contact position

with a fountain roll and a second contact position with a distributor roll, which comprises a housing; a shaft rotatable in the housing; a bearing member for supporting the ductor roll for rotation on an axis parallel to the axis of the shaft, said bearing member being mounted eccentrically on the shaft for movement about the shaft; a rack reciprocable in the housing; gear means connecting the shaft and the rack for rocking the shaft to move the bearing member back and forth between the first and second contact positions of the ductor roll, the axes of the shaft, the ductor roll and one of the fountain and distributor rolls lying in a plane of reference when the ductor roll is in contact position with said one of the fountain and distributor rolls; a movable finger adjacent the rack; and a recess in the rack engageable by the movable finger for releasably locking the bearing member adjacent one of the contact positions of the ductor roll.

5. Control mechanism for a ductor roll movable laterally between a first contact position with a fountain roll and a second contact position with a distributor roll, which comprises a housing; a shaft rotatable in the housing; a bearing member for supporting the ductor roll for rotation on an axis parallel to the axis of the shaft, said bearing member being mounted eccentrically on the shaft for movement about the shaft; means for rocking the shaft to move the bearing member back and forth between the first and second contact positions of the ductor roll, the axes of the shaft, the ductor roll, the fountain roll and the distributor roll lying in a plane of reference when the ductor roll is in contact position with one of the fountain and distributor rolls; and means for releasably locking the shaft against rocking when the ductor roll is in one of its first and second contact positions.

6. Control mechanism for a ductor roll movable laterally between a first contact position with a fountain roll and a second contact position with a distributor roll, which comprises a housing; a shaft rotatable in the housing; a bearing member for supporting the ductor roll for rotation on an axis parallel to the axis of the shaft, said bearing member being mounted eccentrically on the shaft for movement about the shaft; a rack reciprocable in the housing; gear means connecting the shaft and the rack for rocking the shaft to move the bearing member back and forth between the first and second contact positions of the ductor roll, the axes of the shaft, the ductor roll, the fountain roll and the distributor roll lying in a plane of reference when the ductor roll is in contact position with one of the fountain and distributor rolls; a movable finger adjacent the rack; and a recess in the rack engageable by the movable finger for releasably locking the bearing member adjacent one of the contact positions of the ductor roll.
